T. CAMPOBASSO ET AL

NIPPLE

Filed April 18, 1927

Thomas Campobasso,
Gerard Campobasso,

INVENTOR

P. Hickey

WITNESS:

BY *Victor J. Evans*

ATTORNEY

UNITED STATES PATENT OFFICE.

THOMAS CAMPOBASSO AND GERARD CAMPOBASSO, OF BARRE, VERMONT.

NIPPLE.

Application filed April 18, 1927. Serial No. 184,742.

This invention relates to attachments for use upon nipples carried by nursing bottles to destroy vacuums caused by suction upon the nipple, frequently causing the nipple to collapse, and to permit ingress of air to preserve evenness of flow from the bottle.

With the above and other objects in view, the invention further consists of the following novel features, and details of construction to be hereinafter more fully described, illustrated in the accompanying drawing, and pointed out in the appended claim.

In the drawing:—

Figure 1 is a longitudinal sectional view 15 of a nipple with the invention applied upon a bottle neck.

Figure 2 is a vertical sectional view taken on line 2—2 of Figure 1.

Figure 3 is a transverse sectional view 20 taken on line 3—3 of Figure 1.

Referring to the drawing in detail, wherein like characters of reference denote corresponding parts, the reference character 10 indicates the conventional form of nipple as 25 generally used upon nursing bottles. Said nipple is provided with grooved portions 11 and 12 upon the neck therefor to frictionally engage the flange formed upon the periphery of a nursing bottle and the neck 30 therefor.

The invention comprehends strips 13 carried upon the inner side of the nipple neck and conforming to the configuration of the surface thereof to effectively engage the 35 aforementioned shoulder and neck of the bottle. Said strips may be secured in any suitable manner or may be formed as an integral part of the nipple neck.

The outer end of the strip is bent upon 40 itself around the lower peripheral edge of the nipple neck to provide a pocket which will prevent displacement therefrom. It is

to be noted from the foregoing description and accompanying drawing that the strip will sufficiently space the inner side wall of 45 the nipple neck from the shoulder portion and neck of a bottle, to permit ingress of air within the bottle to prevent the formation of a vacuum caused by suction upon the nipple. Such action and formation of 50 a vacuum frequently results in the collapsing of the nipple. It is generally known in the application of nipples upon bottle necks that the peripheral edges thereof frequently become torn and lose the necessary resiliency to rigidly retain the same upon the bottle neck. The invention is designed to 55 overcome this difficulty by strengthening the nipple neck at appropriate points where the peripheral edges of said neck are grasped 60 in the application thereof.

The invention is susceptible of various changes in its form, proportions and minor details of construction, and the right is herein reserved to make such changes as properly fall within the scope of the appended claim.

Having described the invention, what is claimed is:

An attachment for use upon nipples comprising a strip, said strip being adapted to 70 conform to the configuration of the attaching portion of the nipple when applied and to slightly space the adjacent portion of the nipple from a bottle neck to relieve suction, and the outer end of the strip being bent 75 upon itself to receive the peripheral edges of the nipple and adapted to lie flush with the outer side thereof to provide a convenient gripping portion when applied and removing the nipple.

In testimony whereof we affix our signatures.

THOMAS CAMPOBASSO.
GERARD CAMPOBASSO.
